UNITED STATES PATENT OFFICE.

ROBERT C. MORRIS, OF OLNEY, ILLINOIS.

JOURNAL-BOX COOLER.

SPECIFICATION forming part of Letters Patent No. 284,568, dated September 4, 1883.

Application filed January 22, 1883. (No model.)

To all whom it may concern:

Be it known that I, ROBERT C. MORRIS, a citizen of the United States, residing at Olney, in the county of Richland and State of Illinois, 5 have invented certain new and useful Improvements in Journal-Box Coolers, of which the following is a specification, reference being had therein to the accompanying drawings.

My invention relates to certain new and useful improvements in cooling and lubricating axles and axle-boxes with water while the car is in transit or standing on the track at a station or between stations.

The object of my invention is to furnish each 15 car of a railway-train with sufficient water in some convenient part of said car, and held in a proper receptacle, and means by which water held in reserve in each car can be discharged into either axle-box or journal-box of 20 said car for the purpose of cooling or lubricating the same. Chiefly my object is to cool the box and axle. I attain these objects by means of the peculiar construction and arrangement of the parts of my device, that will 25 be more fully described, and pointed out in the specification and claims.

Like letters of reference refer to like parts throughout the drawings.

Referring to the drawings, Figure 1 is a sectional view of a car, showing my improvement 30 in perspective and placed at either end of the car. Fig. 2 is a detail view of my device, showing pipe and connections with journal-box.

Referring to the drawings, A represents a 35 car, constructed and mounted on wheels in the usual manner. Within said car, and preferably at each end, over the trucks, are located tanks B and B', constructed of wood or metal, (preferably of metal,) and of any desired form— 40 round, square, or octagon—as may best suit the construction of the car in which they are to be used. Preferably I construct the tanks angular in form, and of sufficient length to extend 45 over the journal-boxes of the axles connected to each truck. I construct said tanks B and B' in such a manner that no fluid can escape, except through the pipes and passages, as hereinafter described—that is, the sides, 50 ends, tops, and bottoms of said tanks are joined together tightly to prevent leakage.

Near the top and center a perforation, c', is formed, through which water is injected into the tanks. For this purpose, when needed, a hose, c, is attached, by screw-threads or otherwise, to the tank at perforation c', and when not in use said perforation is covered by a cap, formed to fit sufficiently tight to prevent leakage.

At one end of each tank B and B', near the top of the same, are attached overflow-pipes b and b'. The purpose of said overflow-pipes is to discharge the surplus water in the tanks when filled.

For the purpose of preventing the water 65 in tanks B and B' from freezing during cold weather, a steam-pipe, a, passes through the center of said tanks and imparts heat to the water contained therein. A discharge-pipe, i, formed with a stop-cock, e, is attached to 70 the under face of the bottom of tanks B and B', by means of which the tanks are emptied when desired.

At each end of the tanks, on their under 75 faces, are attached metal tubes or pipes l, that extend downward in line with central perforations in the top of journal-boxes. Said pipes are fitted with stop-cocks having turning-plugs connected by rods f and f'. Said rods are formed to extend outward beyond the 80 end of the car, and terminate in T-shaped handles, h, by which said rods and stop-cocks are manipulated. The purpose of this arrangement of my device is to permit the conductor or train-hand, by standing on the platform or step of the car while in motion, to turn the rods f or f', thereby turning the stop-cocks and permitting the water to flow through the pipes l, k, and j into the boxes n, when hot, 85 for the purpose of cooling and lubricating the same.

Connected to the lower end of pipe l is an extension-pipe, k, that extends down into a metal pipe, j, inserted in the top of the journal-box n.

Outside of pipes k, and secured to pipes l and j, are flexible tubes i and i', the use and purpose of which are, first, to prevent freezing of the descending water when using the pipes; and, secondly, by the flexibility of said tubes 100 permitting the vertical adjustment of the car on the springs.

The operation of my device is as follows: Water is let into the tanks B and B' by means of the hose c, or through the perforation c', at a station or from a water stand-pipe beside the track. Stop-cocks g and g' are closed by means of rods f and f'. When one or more boxes become heated while the cars are in motion, an attendant turns either of the rods f or f', as desired, when water will flow from the tank through the pipes into the journal-boxes that are heated by friction, thereby cooling the axles and axle journals and boxes, and at the same time lubricating said parts. The amount of water discharged into said boxes is controlled by the operator turning the stop-cocks by means of the rods f and f'.

I am aware of the patents to S. W. Doane, No. 261,689, July 25, 1882; A. B. Tripler, No. 118,760, September 5, 1871; and E. A. Warren, No. 163,285, May 11, 1875, for axle-boxes, their arrangement of parts, and their operation, and I claim none of these broadly; but,

Having described my invention, what I claim as my invention, and desire to secure by Letters Patent, is—

1. A journal-box cooler and lubricator, consisting of a tank containing water and located in the body of a car over the trucks, said tank having an inlet and overflow pipe, a center discharge or drainage pipe, a heating-pipe 30 passing longitudinally through the interior of the same, and two or more self-adjusting pipes connecting said tank to journal-boxes beneath, and formed with stop-cocks adapted to be simultaneously opened or closed, substantially 35 as and for the purpose set forth.

2. The combination of the tank B, inlet-pipe c, overflow-pipe b, heating-pipe a, discharge-pipe d, having stop-cock e, pipes l, having stop-cocks g, and rod f, with pipes k, flexible 40 tubes i, pipes j, and journal-boxes, all arranged and operated substantially as shown and specified.

In testimony whereof I affix my signature in presence of two witnesses.

ROBERT C. MORRIS.
